UNITED STATES PATENT OFFICE.

CYRUS E. MEAD, OF DAYTON, OHIO, ASSIGNOR TO THE MEAD ENGINE COMPANY, OF DAYTON, OHIO, A CORPORATION OF OHIO.

LUBRICATING SYSTEM FOR EXPLOSIVE-ENGINES.

1,187,761.

Specification of Letters Patent. Patented June 20, 1916.

Application filed March 7, 1912. Serial No. 682,314.

To all whom it may concern:

Be it known that I, CYRUS E. MEAD, a citizen of the United States, residing at Dayton, in the county of Montgomery and State of Ohio, have invented certain new and useful Improvements in Lubricating Systems for Explosive-Engines, of which the following is a specification, reference being had therein to the accompanying drawing.

This invention relates to a lubricating system for explosive engines and is designed more particularly for use in connection with rotary valve engines.

The object of the invention is to provide a simple and positive method or means for lubricating the valves and cylinder of a gas engine, and, to this end, it is a further object of the invention to introduce a lubricating agent into the explosive mixture before the latter enters the engine cylinder; and further, to provide means for automatically regulating the amount of oil drawn into the cylinder.

In the accompanying drawings, Figure 1 is a transverse sectional view of the upper portion of a rotary valve gas engine showing my invention applied thereto; Fig. 2 is an elevation of a portion of a manifold having the carburetor attached thereto and equipped with my invention; Fig. 3 shows a modified form of the invention which embodies an automatic controlling device for the lubricant; and Fig. 4 is another modification of the device showing the same applied to a splash lubricating system.

In carrying out the invention I introduce the lubricating agent, which is usually in the form of an oil, into the explosive mixture before the latter enters the engine cylinder. This may be accomplished in various ways, as by connecting the intake manifold with a suitable source of lubricant supply. In the normal operation of the engine the lubricant is drawn through the valves of the engine into the cylinders and portions of the same will adhere to the valves and to the walls of the cylinder, thus adequately lubricating the same and this without in any way impairing the quality of the explosive mixture. In the present instance I have shown the invention as applied to a rotary valve engine, to which it is particularly well adapted, although it is by no means limited to such engines. In

Fig. 1 I have shown the upper portion of such an engine in section and it will be noted that it comprises a body portion provided with one or more cylinders, 1, one only of which is shown, and valve chambers 2 and 3 communicating with the opposite sides of the cylinder or cylinders and also communicating with the intake and exhaust manifolds, 4 and 5, respectively. Mounted in each valve chamber is a rotary valve 6 which is rotated continuously in one direction. In applying the invention to such an engine a suitable source of lubricant supply, such as an ordinary oil cup 7, is connected with the manifold 4 and as the suction created in the manifold by the movement of the piston in the engine draws the explosive mixture and the lubricant through the manifold it will come in contact with the cylindrical surface of the valve when this overlaps the port. In the ordinary operation of the valve there is a very brief interval only of the period during which the valve is open that the port in the valve registers exactly with the port leading to the manifold. For the remainder of the time that the valve is open one or the other of the edges of the valve will overlap the port leading to the manifold and will, consequently, come in contact with the lubricant containing mixture. Sufficient of the lubricant will adhere to the surface of the valve and be carried into the valve chamber to adequately lubricate the valve. The lubricant containing mixture will, of course, contact with the inner surface of the cylinder, thus again permitting the lubricant to adhere to the surface to be lubricated. Further, the compression of the mixture within the cylinder forces the same against the surface of the exhaust valve, thus causing sufficient of the lubricant to adhere to this valve to lubricate it. It is apparent, therefore, that by merely introducing the lubricant into the explosive mixture both the valves and the cylinder are adequately lubricated.

The oil cup or other source of supply may be connected with the manifold on either side of the throttle valve. The suction above the throttle valve varies with the position of the valve, that is, if the valve is almost closed there will be a much greater suction in the manifold above the valve than there will be if the valve is entirely open. For

this reason a more uniform flow of oil from the cup to the manifold will be secured if the cup is connected with the manifold below the throttle valve, where the suction is much more uniform, and, in Figs. 1 and 5 2 of the drawings I have shown an oil cup of ordinary construction connected with the manifold below the throttle valve, as shown at 7^a, which is of the butterfly type and is arranged at the point of union of the manifold with the carburetor. It will be apparent, however, that the connection between the oil cup or other source of supply and the manifold may be made at any suitable point and the flow of oil automatically controlled. One form of automatic control I have shown in Fig. 3 in which I have provided an oil cup 8 of ordinary construction and have connected the same by means 10 of a pipe 9 with the manifold above the throttle valve. The oil cup has the usual vertically movable controlling member 10 which is connected to one end of a bell crank lever 11, the other arm of which is connected by means of a link 12 with a piston rod 13 of a piston 14 mounted in a cylinder 15 which is connected by a pipe 16 with the manifold above the throttle valve. The piston will, of course, be subjected 15 to the suction within the manifold and this suction will tend to move the piston toward that end of the cylinder nearest the manifold. This movement causes the needle 10 to move downward and thus reduce the flow of oil through the outlet opening of 20 the oil cup. When the suction in the manifold becomes less the spring on the needle will move it downward and draw the piston toward that end of the cylinder remote from the manifold. In this manner a substantially 25 uniform flow of oil is maintained from the cup to the manifold, it being obvious that the strong suction will partially close the outlet to the oil cup and will, therefore, draw less oil from the cup, while the lighter suction will allow the outlet to the oil cup to remain open to a greater extent and, consequently, the lighter suction will move substantially the same amount of 30 oil as the heavier suction moves.

The suction in the manifold may be utilized 35 to automatically control the lubrication of the engine when the lubricant is applied in some manner other than by mixing it with the explosive mixture. In Fig. 4 I have illustrated one apparatus which can be so controlled. I have there shown a part of a splash system for lubricating an engine cylinder which comprises an oil pan 17 40 mounted on a rockshaft 18 having an arm 19 which is connected by a link 20 with the piston rod 13 of the cylinder 15 similar to that shown and described in connection with Fig. 3. The oil is dipped from the pan 17 45 by a finger 21 carried by a connecting rod

22. By moving the pan 17 toward or away from the connecting rod, when the same is in its lowermost position, the amount of oil lifted by the finger 21 can be varied and by connecting the rockshaft carrying the pan with the piston of the cylinder 15 this movement of the pan will be automatically accomplished by the suction in the manifold. 50

It will be apparent from the foregoing description that I have provided means for lubricating the cylinder and valve of the engine which is very simple yet highly efficient; which requires very little mechanism and is automatic in its action; and further, that I have provided a mechanism for automatically controlling the feed of oil from the oil cup, which mechanism will be automatically controlled according to the suction in the manifold and which suction varies inversely to the speed of the engine. 55

While I have shown and described certain arrangements of apparatus for carrying out my invention it will be understood that these are chosen for the purpose of illustration only and that I do not desire to be limited to the details of construction shown and described, for obvious modifications will occur to a person skilled in the art. 60

Having thus fully described my invention, what I claim as new and desire to secure by Letters Patent, is:—

1. The combination, with an explosive engine comprising a cylinder, an intake passage leading to said cylinder, a valve to control the communication between said passage and said cylinder, and a throttle valve to control the flow of explosive mixture through said passage, of a conduit communicating with said passage on that side 100 of said throttle valve remote from said engine and also communicating with a source of lubricant supply. 105

2. The combination, with an explosive engine having an intake manifold, a lubricant receptacle, and an adjustable connection between said lubricant receptacle and said manifold, of means controlled by the suction within said manifold to automatically adjust the connection between said lubricant receptacle and said manifold to points between the limits of its adjustment, to regulate the flow of lubricant to the manifold according to the requirements of the engine. 110

3. The combination, with an explosive engine having an intake manifold, a lubricant receptacle, and an adjustable connection between said lubricant receptacle and said manifold, of a cylinder communicating 115 with said manifold, a piston in said cylinder, and means actuated by said piston to adjust the connection between said lubricant receptacle and said manifold to points between the limits of its adjustment, to 120 125

regulate the flow of lubricant to said manifold according to the requirements of the engine.

4. The combination, with an explosive engine having a manifold, and an adjustable lubricating device for said engine, and means controlled by the suction in said manifold to adjust said lubricating device to points between the limits of its adjustment to regulate the flow of lubricant according to the requirements of the engine.

5. The combination, with an explosive engine having a manifold, a throttle valve for said manifold, and an adjustable lubricating device for said engine, of suction controlled mechanism communicating with said manifold between said engine and said throttle valve and operatively connected with said lubricating device to adjust the same to points between the limits of its adjustment to regulate the flow of lubricant according to the requirements of the engine.

6. In an internal combustion engine provided with a fuel inlet passage, a source of lubricating fluid, a device for controlling the flow of lubricating fluid from said source to a part of said engine and means acting on said device continually urging it

to a position to permit the flow of lubricating fluid and means arranged to oppose said last named means controlled automatically by the load on the engine when the same is running for varying the position of said device.

7. In an internal combustion engine having a fuel inlet passage, the source of lubricating fluid, a valve by which the flow of lubricant from said source is controlled and means for automatically opening said valve upon a decrease of vacuum in the fuel inlet passage of the engine.

8. In an internal combustion engine having a fuel inlet passage, a source of lubricating material, a valve by which the flow of lubricant from said source to a part of said engine is controlled, means acting on said valve to normally maintain it open and means opposing said last named means to automatically close said valve upon an increase of vacuum in said fuel inlet passage.

In testimony whereof, I affix my signature in presence of two witnesses.

CYRUS E. MEAD.
